US0D1068726S

(12) **United States Design Patent** (10) Patent No.: **US D1,068,726 S**
(45) Date of Patent: ** Apr. 1, 2025

(54) **REMOTE CONTROL**

(71) Applicant: **Junxiao Hao**, Taiyuan (CN)

(72) Inventor: **Junxiao Hao**, Taiyuan (CN)

(**) Term: **15 Years**

(21) Appl. No.: **29/924,903**

(22) Filed: **Jan. 22, 2024**

(51) LOC (15) Cl. **14-03**

(52) U.S. Cl.

USPC **D14/218**

(57) **CLAIM**

The ornamental design for a remote control, as shown and described.

DESCRIPTION

FIG. 1 is a front, top and right side perspective view of a remote control, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the remote control that form no part of the claimed design.

1 Claim, 8 Drawing Sheets
